Edgar G. Varela

UNITED STATES PATENT OFFICE.

BERTHA C. OLSON, OF NEW YORK, N. Y.

BRASSIÈRE.

1,328,586.

Specification of Letters Patent. Patented Jan. 20, 1920.

Application filed January 30, 1919. Serial No. 273,951.

To all whom it may concern:

Be it known that I, BERTHA C. OLSON, a citizen of the United States, and residing at New York, in the county of New York and State of New York, have invented certain new and useful Improvements in Brassières, of which the following is a specification, such as will enable those skilled in the art to which it appertains to make and use the same.

This invention relates to what are known as brassières, and the object of the invention is to simplify the construction and manufacture of articles of this class so as to produce a reasonable and yet effective article of the class specified; a further object being to manufacture an article of the class specified of net or openwork material cut on the bias thereby producing a brassière having all the qualities of articles of this class, as now constructed, as well as producing a brassière which will not bind or be otherwise uncomfortable in use; a still further object of the invention being to so make the brassière as to give it the desired shape or form to readily and comfortably conform with the shape or form of the wearer; and with these and other objects in view the invention consists in an improved method 30 of manufacturing articles of the class specified from a single piece of fabric, or net or openwork material, cut, folded and sewed to the desired form in the manner herein set out and in the article so produced.

35 The invention is fully disclosed in the following specification, of which the accompanying drawing forms a part, in which the separate parts of my improvement are designated by suitable reference characters 40 in each of the views, and in which:—

Figure 1 is a front view of my improved brassière in its attached position and indicating the wearer in dotted lines;

Fig. 2 a back view of the construction 45 shown in Fig. 1;

Fig. 3 a plan view of my improved brassière extended and with part of the construction broken away;

Fig. 4 a plan view of a strip of net or 50 openwork fabric shown folded centrally and longitudinally and also showing the first step in the operation of forming the brassière, and with part of the construction broken away;

Fig. 5 a view similar to Fig. 4 but show-

ing the second step in making my improved brassière;

Fig. 6 a view similar to Fig. 5 but showing only a part of the construction and showing the third step; and,

Fig. 7 a view similar to Fig. 6 but showing the last step in making the main body portion of the brassière.

In the practice of my invention, I preferably form my improved brassière from a sheet 10 of net, or openwork material, which is folded centrally to form a strip 11 of two thicknesses of the material. In forming a brassière from the strip 11, said strip is first cut centrally, approximately two-thirds, 65 of the width thereof as shown at 12, and from one side edge of said strip, and the other side edge of the strip 11 is cut at the opposite sides of the central cut 12 and spaced equally therefrom as shown at 13 70 and 14, the cuts 13 and 14 extending approximately one-half way across the width of the strip 11 as is clearly illustrated in Fig. 4.

The next step in forming the brassière consists in forming three darts 15, 16 and 17 in the strip 11, the dart 15 being centrally of the strip and formed by the cut 12, or by overlapping the side edges of the strip at the cut-out portion 12, while the darts 16 and 17 are correspondingly formed by overlapping the side edges of the strip 11 at the cuts 13 and 14, after which the darts 15, 16 and 17 are completed by securing the overlapped portions of the strip 11 centrally and longitudinally by hemstitching, or any other stitching as shown at 18 in Fig. 5 of the drawing. The overlapping portions of the strip 11 at the cuts 12, 13 and 14 are then cut off or trimmed close to 95 the stitching at 18 to form a completed dart as illustrated in Figs. 1, 2, 3, 6 and 7 of the drawing.

The next step in forming the brassière consists in folding the opposite end portions 100 of the strip 11 inwardly upon the body portion of the strip as shown at 19 in Fig. 6 of the drawing so that the end portions 20 of the strip are directed downwardly or at an angle to the body portion of the strip. 105

The next step in the operation consists in securing the folded end portions 20 to the main body portion of the strip 11 at 19 by two rows of hemstitching or other stitching 21, in which operation the folded end por-

tions 20 of the strip at 19 are gathered, after which the strip 11 with the folded end portions 20 thereof stitched to the main body portion are cut along the dot and dash lines indicated in Fig. 6 to produce the result shown in Fig. 7 of the drawing. The above operation also forms darts at 19 where the end portions 20 are stitched to the main body portion.

10 The above operation of folding, cutting and forming darts and stitching of the sheet 10 produces the general form of my improved brassière which is indicated at 22 in Fig. 3 of the drawing and which comprises 15 a main central body portion 23 with the darts 15, 16 and 17 therein, the dart 15 producing the desired waist shape, while the darts 16 and 17 produce the bust shape and at the opposite sides of the main central 20 body portion 23 are approximately triangular end portions 24 and 25 formed by folding the end portions 20 of the strip 11 or by the darts at 19 in the manner above set out. In practice, I also preferably connect 25 with the bottom of the body portion 23 centrally thereof a depending strap 26 with which is adjustably connected the usual fastening device 27, and connected with the top of the body portion 23 between the darts 16 30 and 17 and the darts at 19 at the opposite sides thereof are shoulder straps 28, which are preferably made of elastic material, but which may be made of lace, ribbon or any other suitable material. I also connect with 35 the free ends of the triangular end portions 24 and 25 of the brassière tie straps 29.

In the use of the device, the arms are passed through the arm-holes 30 formed by the straps 28 and one of the triangular end 40 portions 24—25 is passed backwardly and then forwardly, after which the other end portion 24—25 is passed backwardly and over the first named end portion, and then forwardly and the tie straps 20 on the ends 45 of both of said end portions are then tied together at the front to hold the brassière in proper place, it being understood that the pull upon the straps 29, or the end portions 24—25 will regulate the pressure or binding 50 qualities of the device.

By forming a brassière or similar device in the manner herein shown and described, I produce a device of this class which readily conforms to the shape of the wearer and 55 produces a comfortable and yet effective article of this class, and it will be noted that the stitchings or darts at 19 come at the opposite sides of the central portion of the back of the wearer, and while I have stated 60 that I preferably employ net or openwork material, my invention is not limited to the use of this material, nor is my invention necessarily limited to the formation of the triangular end portions 24 and 25 integral 65 with the body portion 23, as these end por-

tions may be made separately and connected with the body portion 23, if desired, and while I have stated that the darts 15, 16 and 17 are formed by first cutting the strip 11 at 12, 13 and 14, and it will be understood that 70 these darts may be formed by folding the strip 11 at these points in the manner of forming the darts at 19, and various other changes in and modifications of the details of construction herein shown and described 75 may be made, within the scope of the appended claims, without departing from the spirit of my invention or sacrificing its advantages.

Having fully described my invention, 80 what I claim as new and desire to secure by Letters Patent, is:—

1. The herein described method of forming brassières which consists in providing a sheet of fabric of predetermined dimensions, folding said sheet centrally and longitudinally to form a strip composed of two thicknesses, forming a dart centrally of said strip on one side edge portion thereof, forming other darts in the opposite edge portion 85 of said strip and at the opposite sides of the first named dart and forming other darts in the opposite end portions of said strip to form a central body portion and approximately triangular end portions arranged at 95 an angle to the central body portion.

2. The herein described method of forming brassières, which consists in providing a sheet of fabric of predetermined dimensions and composed of two thicknesses 100 throughout, forming a dart centrally of said strip on one side edge portion thereof, forming other darts in the opposite edge portion of said strip and at the opposite sides of the first named dart and forming other darts in 105 the opposite end portions of said strip to form a central body portion and approximately triangular end portions arranged at an angle to the central body portion.

3. A brassière of the class described comprising a central body portion and oppositely directed end portions extending from the central body portion at an angle thereto, said body portion and end portions being composed of two thicknesses of fabric, the 115 main body portion being provided centrally of the bottom edge thereof with a dart and other darts formed in the opposite side edge of the body portion on opposite sides of said central dart and at a predetermined distance 120 therefrom.

In testimony that I claim the foregoing as my invention I have signed my name in presence of the subscribing witnesses this 28th day of January 1919.

BERTHA C. OLSON.
